DESIGN FOR A CHAIR STANDARD

Willard H. Bond, Jr., East Grand Rapids, Mich.,
assignor to American Seating Company, Grand
Rapids, Mich., a corporation of New Jersey

Application September 21, 1938, Serial No. 80,018

Term of patent 14 years

To all whom it may concern:

Be it known that I, Willard H. Bond, Jr., a citizen of the United States, residing at East Grand Rapids, in the county of Kent and State of Michigan, have invented a new, original, and ornamental Design for a Chair Standard, of which the following is a specification, reference being had to the accompanying drawing, forming a part thereof, in which:—

Figure 1 is a front elevational view of the chair standard, showing my new design; on a reduced scale;

Figure 2 is a side elevational view of the chair standard;

Figure 3 is an enlarged sectional view thereof on line 3—3 of Figure 2;

Figure 4 is an enlarged sectional view on line 4—4 of Figure 2;

Figure 5 is an enlarged sectional view on line 5—5 of Figure 2; and

Figure 6 is an enlarged sectional view on line 6—6 of Figure 2.

The distinguishing, essential and dominating features or characteristics of the design are the general configuration or outline of the standard and the fluted upper portion thereof as shown.

I claim:

The ornamental design for a chair standard, as shown and described.
